UNITED STATES PATENT OFFICE.

ARTHUR E. ALLUM, OF NEW YORK, N. Y.

CONTINUOUS WAISTBAND FOR TROUSERS.

1,123,160.

Specification of Letters Patent.

Patented Dec. 29, 1914.

Application filed October 20, 1913. Serial No. 796,299.

To all whom it may concern:

Be it known that I, ARTHUR E. ALLUM, citizen of the United States, residing at Bronx, New York city, in the county of 5 New York and State of New York, have invented certain new and useful Improvements in Continuous Waistbands for Trouser, of which the following is a specification.

This invention relates to improvements in 10 garment waistbands and more particularly to that type adapted to house a belt.

It is one aim of the invention to provide a waistband especially adapted for use upon trousers and so constructed that it will completely conceal the belt.

Another aim of the invention is to provide a waistband of the type mentioned, so constructed that its component parts may be united together and to the waist of a pair 20 of trousers by running but two lines of stitching, the band being completed as it is attached to the trousers and this feature of the invention insures of a saving of considerable time and labor and in fact less time 25 is required in assembling the parts of the present waistband and stitching them within the waist of a pair of trousers than is ordinarily consumed in preparing and applying the ordinary waistband which is not 30 adapted to house the belt. Furthermore, as will be apparent from the description which is to follow, by making use of the waistband embodying the present invention, the ordinary narrow belt loops and wider loops, 35 which are known as tunnels, are dispensed with and as a consequence there is a saving in cost for the material which would have to be used in their manufacture and attachment, as well as a considerable saving in 40 time.

Another feature of the invention resides in the fact that the waistband embodying the same serves not only to house the garment belt, but also takes the place of the 45 usual curtain and apron pieces and consequently obviates the felling of waistband linings and the basting of the canvas pieces and button stays.

It is also an object of the invention to 50 construct and arrange the waistband in such a manner that not only will the belt be concealed at the front of the trousers but

the trousers will be held closed at the front of the waist without the employment of any clasps or hooks as is now necessary.

55

Incidentally, the invention aims to dispense with the use of the usual side and back straps ordinarily provided for tightening the waist of the trousers.

Still further the invention has as its object to provide upon the belt to be used in connection with the waistband one or more money pockets which are detachable and any one of which may be brought into position at the front of the garment for removal, 65 without the necessity of removing the belt from the waistband.

In the accompanying drawings:—Figure 1 is a perspective view of the waist portion of a pair of trousers provided with the 70 waistband constructed in accordance with the present invention, the view illustrating a belt arranged within the waistband; Fig. 2 is a sectional perspective view, showing the construction of the waistband and illustrating the belt housed therein; Fig. 3 is a sectional view through the waistband at the front of the trousers; Fig. 4 is a perspective view illustrating the appearance of the trousers when the belt has been tightened; 80 Fig. 5 is a vertical sectional view, parts being shown in elevation, illustrating the arrangement within the band of the reinforcing flaps or pieces which are employed when the trousers are provided within the waist 35 portion with buttons; Fig. 6 is a perspective view of a portion of the belt illustrating also the money pockets arranged thereon; Fig. 7 is a perspective view of one of the money 90 pockets detached from the belt, the same being shown opened in full lines and closed in dotted lines.

Corresponding and like parts are referred to in the following description and indicated in all the views of the drawings by 95 the same reference characters.

In the drawings, the numeral 1 indicates, in general, the waist portion of a pair of trousers and 2 indicates, in general, the waistband embodying the present invention 100 arranged within the trousers. The waistband consists in part of a lining and reinforcing portion 3 which is preferably of canvas or some other relatively stiff and

heavy cloth and initially the lining is in the form of a strip of a suitable length and width which, at the time of manufacture of the waistband, is folded longitudinally medially as at 4 with its free edges registering 5 as indicated at 5. By reference to Fig. 2, it will be apparent that the edges 5 of the lining are to be united by a line of stitching which secures also other portions of the 10 band as will be presently explained, and it will be apparent that when the edges of the lining are so united, the lining will be tubular and consequently adapted to conceal the belt to be housed. It will be apparent 15 by reference to the said figure that the lining is disposed against the inner side of the waist portion of the garment and consequently is concealed, the upper edge of the waist portion being folded over the upper 20 edge of the lining as at 6 and united by a line of stitching 7 to one wall of the lining 2 at its said upper edge. This line of stitching 7 serves also to unite to the folded over edge of the waist portion of the garment 25 the upper edge of a facing strip 8. The lower edge of the strip 8 is folded about the registering edges 5 of the lining strip as indicated at 9 and the line of stitching herefore mentioned as uniting these edges, and 30 indicated by the numeral 10, serves to secure the folded lower edge of the facing strip to the said edges of the lining strip and to secure the lower edge of the waistband as a whole to the inner side of the waist portion 35 of the garment.

In assembling the waistband and attaching the same within the waist portion of the trousers, the lining strip is first creased longitudinally to determine the line of fold 40 and is disposed with its upper edge portion against the upper edge of the waist portion of the garment at the inner side thereof and one edge of the facing strip 8 is disposed against the outer side of the said upper 45 edge of the waist portion and the line of stitching 7 is then run. The other edge of the facing strip 8 is then folded over the registering free edges of the lining strip and then having been placed against the 50 inner side of the waist portion of the garment is united thereto by the line of stitching 10.

It will be apparent from the foregoing 55 that when the line of stitching 10 is run, the waistband will be closed and completed and simultaneously attached to the garment in view of which it is quite obvious that but little expense and labor is involved in the manufacture and application of the band. 60 It is to be noted that the waistband extends entirely around the waist line of the garment and it will be apparent that it is stiffened by the lining 3 to such a degree that the garment at the waist line will

not be liable to pucker, but will, on the other hand, closely and neatly fit the wearer. It is partly due to this fact that the employment of the usual side and back straps for tightening the waistband is rendered unnecessary. The waistband is of sufficient depth to serve as an excellent substitute for the curtain and apron pieces which are usually stitched within the waist portion of a pair of trousers and it is obvious that it will be much neater in appearance. 75

By reference to Fig. 1 of the drawings, it will be observed that the waistband at the left hand side of the trousers, extends entirely to the open front thereof, but that at the other side it terminates slightly short 80 of the open front, as indicated by the numeral 11 so that when the trousers are being worn the two ends of the waistband will meet and as a consequence the belt housed within the band will be entirely concealed 85 from view.

When it is desirable that the trousers be provided within the waistband with buttons, as indicated at 12, in Fig. 5 of the drawings, it is preferable that the waistband be reinforced at the points of attachment of the buttons and in order that this may be accomplished there are provided the required number of reinforcing flaps or pieces 13 which may be relatively narrow, 90 as shown in the said Fig. 5, and which are folded transversely between their ends and disposed to straddle the lining tube 3, their free end edges being secured by the line of stitching 10. 100

The belt, which is to be housed within the waist band and which constitutes also a feature of the invention, is indicated, in general, in the drawings by the numeral 14 and is provided at one end with any suitable form of buckle 15, whereby the belt may be closed and tightened. As has before been pointed out, the belt is provided with one or more money pockets which are detachable and the construction of these 110 pockets is clearly shown in Figs. 6 and 7. Each pocket, indicated by the numeral 16, consists of a piece of cloth of a suitable width and length and which is folded longitudinally along three or more lines as indicated at 17, 18 and 19, this latter fold providing a closure flap 20 provided adjacent each of its ends and upon its outer side with either the stud or socket member of a snap fastening 21. The belt 14 is provided at suitable intervals with the other members 22 of the snap fastenings and when the pocket has been folded, as shown in dotted lines in Fig. 7, to inclose bills or other articles of value disposed therewithin, 12 the elements 21 are engaged with the elements 22 of the snap fastenings and the pocket will then be held to the belt in the 13

manner shown in Fig. 6. In its folded condition, the pocket is no wider than the belt and as a consequence there is nothing to prevent its passage with the belt through 5 the waistband.

As stated before, any desired number of the pockets may be provided and when it is desired to gain access to any one of the pockets it is only necessary to loosen the 10 belt slightly and then shift the same around within the waistband until the desired one of the pockets is brought to the front of the garment where it may be readily opened or removed.

15 It will be seen that there is a distinct combination between the tubular waistband of the present invention and the belt which is provided with the money pockets inasmuch as the pockets are inclosed within the 20 tubular lining and are thereby prevented from becoming unfolded.

It will be apparent that the present waistband is not formed in sections, either separate or connected, but that it is continuous 25 and extends throughout the entire width of the waist portion of the garment and forms an integral part thereof.

Having thus described the invention, what is claimed as new is:

30 1. The combination with the waist portion of a garment, of a waistband therefor including a tubular lining comprising a strip folded longitudinally with its edges registering, the upper edge of the waist portion being folded over the fold in the said strip, and a facing, the facing, the folded over upper edge of the waist portion; and the folded upper edge of the lining being attached to each other, the lower edge of the 35 facing being folded over the registering edges of the lining strip and the said folded lower edge of the facing and the said edges of the lining strip being attached to the waist portion, the said waistband extending 40 entirely around the inner side of the waist portion when the waist portion is closed and terminating at one end directly at one edge of the open front of the waist portion and at its other end slightly short of the other 45 edge of said front, the waist portion at the last mentioned side of the front being slit to register with the second mentioned end of the waistband.

50 2. The combination with the waist portion of a garment open at one side and adapted to be closed, of a tubular belt receiving waistband extending entirely around the waist portion and having its ends open and adapted to meet when the said side of the waist portion is closed, and a belt removably fitted within the waistband and adapted to be completely concealed thereby when the open side of the garment is closed.

55 3. The combination with the waist por-

tion of a garment open at one side and 65 adapted to be closed, of a tubular belt receiving waistband extending entirely around the waist portion and having its ends open, a belt removably fitted within the waistband and adapted to be completely concealed 70 thereby when the open side of the garment is closed, and a pocket carried by the belt and held closed by the walls of the waistband.

4. The combination with the waist portion of a garment open at one side and 75 adapted to be closed, of a tubular belt receiving waistband extending entirely around the waist portion and having its ends open, a belt removably fitted within the waistband and adapted to be completely concealed 80 thereby when the open side of the garment is closed, and a pocket carried by the belt and held closed by the walls of the waistband, the pocket being detachable from the 85 belt.

5. The combination with the waist portion of a garment open at one side and adapted to be closed, of a tubular belt receiving waistband extending entirely around the waist portion and having its ends open, 90 a belt removably fitted within the waistband and adapted to be completely concealed thereby when the open side of the garment is closed, and a pocket carried by the belt and held closed by the walls of the waistband, 95 the pocket being detachable from the belt, and comprising a sheet blank folded upon itself and adapted to be maintained in folded condition by the walls of the waistband.

6. The combination with the waist portion of a garment, of a waistband therefor including a tubular lining disposed against the inner side of the said waist portion, a facing strip attached at its upper and lower edges to the lining and to the waist portion 105 of the garment, and a reinforcing flap attached at its upper edge to the lining and depending beside the lining.

7. The combination with the waist portion of a garment, of a waistband therefor 110 including a tubular lining disposed against the inner side of the said waist portion, a facing strip attached at its upper and lower edges to the lining and to the waist portion of the garment, and a reinforcing flap attached at its upper edge to the lining and depending beside the lining, the said flap straddling the lining and having its depending side portions confined one between the lining and the facing and the other between the lining and the said waist portion.

8. The combination with a garment having a waist portion which is continuous with the adjacent portion of the garment whereby to have the same appearance as the said 125 adjacent portion of the garment, of a waistband including a tubular lining disposed against the inner face of the said waist por-

tion of the garment and the said waist portion having its upper edge turned over the upper edge of the said lining and secured thereto, and a facing strip secured at its 5 upper and lower edges to the upper and lower edges of the lining, the waist portion of the garment covering and concealing the outer side of the tubular lining and the facing strip covering and concealing the inner

side of the said lining and the waist band as 10 a whole lying bodily below the upper edge of the waist portion of the garment.

In testimony whereof I affix my signature in presence of two witnesses.
